REENFORCING DEVICE FOR SCREEN
FRAME CORNERSGeorge Klenyansky and William Klenyansky,
Chicago, Ill.

Application March 21, 1935, Serial No. 12,230

1 Claim. (Cl. 156—14)

This invention relates to improvements in screen frame corner reenforcements, particularly to those having grooved vertical sides.

The main object of the invention is to provide 5 a novel screen frame corner reenforcement to protect the guides of the vertical members of the screen frame.

Another object of the invention is to provide 10 novel means to reenforce the corners of a screen frame.

A further object of the invention is to provide a device, which permits a smoother operation of the screen frame when it slides in the guides of the window frame.

15 A still further object of the invention is to provide a device, which permits the changing of the screen without disturbing the screen frame.

A still further object of the invention is to provide 20 a device of the character described, simple in construction, easily assembled, and efficient in carrying out the purpose for which it is designed.

A still further object of the invention is to prevent the falling out of small children.

With the foregoing and other objects in view, 25 which will appear as the description proceeds, the invention consists in certain novel features of construction, hereinafter more fully described, illustrated in the accompanying drawing, and particularly pointed out in the appended claim.

30 It is to be understood that various changes in the proportion, size, and minor details of the structure may be made without departing from the spirit or sacrificing any of the advantages of the invention.

35 For the purpose of facilitating an understanding of our invention, we have illustrated in the accompanying drawing preferred embodiments thereof, from an inspection of which, when considered in connection with the following description, our invention, its construction, and its advantages should be readily understood and appreciated.

40 Referring to the drawing, in which similar characters of reference are employed to indicate corresponding or similar parts throughout the several figures in the drawing,

Fig. 1 is an elevational view of a screen frame equipped with our corner reenforcing devices.

Fig. 2 is a sectional view on line 2—2 of Fig. 1.

Fig. 3 is a sectional view on line 3—3 of Fig. 1.

Fig. 4 is an enlarged fragmentary sectional 5 view on line 4—4 of Fig. 1.

Fig. 5 is an enlarged fragmentary sectional view on line 5—5 of Fig. 1.

Referring to the drawing more specifically, the screen frame corner reenforcement 1, is comprised of a horizontal member 2, and a vertical member 3.

The horizontal member 2, has a bottom part 4, and vertical flanges 5—5, all three together forming a U-shape, to fit snugly around the 15 corners of the horizontal members 6—6, of the screen frame 7.

The vertical member 3, has a grooved portion 8, which fits snugly within the grooves 9—9, of the vertical members 10—10, of the screen frame 20 7. The vertical member 3, has flanges 11—11, which fit snugly around the outside flanges 12—12, of the vertical members 10—10, of the screen frame 7.

The vertical flanges 5—5, of the horizontal 25 member 2, and the flanges 11—11, of the vertical member 3, have a series of holes 14, close to their outer edges 15—15, to permit the fastening of screen frame corner reenforcements 1, by nails 16, to the horizontal members 6—6, and 30 vertical members 10—10, of the screen frame 7.

Moulding 17, retains the screen 18 in its place and permits its replacement without interfering with the screen frame 7.

We claim:

35

A metal device for reenforcing screen frames, 40 said device having a U-shaped horizontal portion and a U-shaped vertical portion, these portions embracing the respective horizontal and vertical portions of a screen frame at the corner thereof, said vertical portion including a grooved part 45 formed like an instruck tongue.

GEORGE KLENYANSKY.
WILLIAM KLENYANSKY.
